HUBERT A. MYERS, OF TOLEDO, OHIO

DOOR BUFFER

Application filed September 26, 1929. Serial No. 395,411.

My invention has for its object to provide an efficient door buffer, which not only absorbs the slam of a door, but also forms a means for producing registration of the parts 5 of the door, such as the parts of the door lock, and at the same time operates as an anti-rattler for doors. The invention particularly provides a means for clamping a part of the door as it reaches the limit of 10 its closing movement.

The invention may be contained in structures of different forms and, to illustrate a practical application of the invention, I have selected a structure containing the invention 15 as an example of the different forms of door buffers that involve the use of the invention, and shall describe the buffer selected hereinafter. The buffer referred to is shown in the accompanying drawing.

20 Fig. 1 of the drawing illustrates a perspective view of a part of an automobile door, and the jamb in connection with which the structure, selected for purposes of illustration, is used. Fig. 2 illustrates a sectional 25 view of the inter-related parts of the door and illustrates the relative position of the parts when the door has reached a point near its limit of its closing movement. Fig. 3 illustrates the relative positions of the parts 30 when the door is completely closed.

In connection with doors of automobiles, as is well known, there is a considerable jouncing of the automobile as it moves over the road with the result that doors become 35 loose, and, in time, rattle in their cases. In order to avoid this movement, such doors are provided with cushion members which are usually formed of soft rubber that frictionally engage, upon closing the door, the opposite 40 site sides of a tongue that is secured to the door edge. When, therefore, the door is to be closed, the surfaces of the cushion members frictionally resist the closing movement, and in opening the door the same frictional 45 resistance is encountered, with the result that, in order to open the door after it is unlatched, a considerable force is required to move it. It has been found that, in time, the rubber cushion become hardened and thereby their 50 efficiency is materially destroyed. Likewise,

in opening the door, the resistance of the door latch located midway between the side edges of the door must be manually overcome. By my invention, an elastic means is used not only for buffing the closing movement, but also to clamp the opposite sides of the door tongue upon the completion of the closing movement and thus elastically hold the door as against any vertical movements with respect to the door jamb, and at the 60 same time, eliminate frictional resistance to the closing and opening movements of the door. It also operates to spring press the door outwardly so that when the latch is disengaged the door will immediately move 65 outwardly. In the construction embodying my invention, the door 1 is provided with the tongue 2 which may be die-pressed to shape, it being provided with end parts 3 that may be secured to the edge of the door, as by the 70 screws 4. The jamb 5 of the door is provided with a case 6 that may be located within the surfaces of the jamb, as by morticing. The case 6 is provided with a spring 7 that is secured in position by its own resiliency, its 75 ends being located in the inner corners of the case. The spring 7 is provided with a re-entrant part 8 and so as to form the two bowed portions 9. The case 6 is provided with a suitable opening or slot 10 through which 80 the tongue 2 may be moved and engage the central portion 11 of the re-entrant part 8. Thus, the spring 7 is formed to have, preferably, inwardly curved portions 15, and the outwardly curved or bowed portions 16, 85 which are joined by the inwardly curved portion 17 of the central part 11 of the re-entrant portion of the spring. The tongue 2 engages the central part 11 at near the completion of the closing movement of the door 90 and upon a further slight movement, the bowed portions of the spring will be drawn against the sides of the tongue; the inwardly curved portions 15, now assuming a substantially straight position, acts to brace the 95 bowed portion against the tongue. Thus, the tongue will be clamped between the bowed portions of the spring where it will be held as long as the door is secured by the latch. Upon unlatching the door, the tension of the 100

spring causes it to push the door open with a quick outward movement, the reactive pressure of the spring requiring a very short distance for operation. This eliminates the necessity of pulling on the door in order to free its tongue from clamping parts of a buffer member.

I claim:

In a door buffer, a tongue having parallel upper and lower surfaces and attached to the door, a socket supported in the door jamb, a spring located in the socket, the spring having a re-entrant part, the sides of the re-entrant part normally inclined to the upper and lower parallel sides of the tongue, the inner end of the re-entrant part located remote from the bottom of the socket, the sides of the re-entrant part adapted to increasingly clamp the upper and lower surfaces of the tongue when the edge of the tongue presses the central portion of the re-entrant part and to increasingly resist the inward movement of the tongue after the tongue engages the inner end of the re-entrant part as the tongue is further moved into the socket, the tongue being connected to the door and the socket to the door jamb to cause movement of the inner end of the re-entrant part towards the bottom of the socket by the movement of the tongue and upon releasement of the door to produce with a relatively low pressure a large momentum in the door.

In witness whereof I have hereunto signed my name to this specification.
